UNITED STATES PATENT OFFICE.

JOHN E. O'HEARNE, OF NORWALK, OHIO.

TRIMMER.

No. 888,645.

Specification of Letters Patent.

Patented May 26, 1908.

Application filed August 30, 1907. Serial No. 390,765.

To all whom it may concern:

Be it known that I, JOHN E. O'HEARNE, a citizen of the United States of America, residing at Norwalk, in the county of Huron and 5 State of Ohio, have invented or discovered new and useful Improvements in Trimmers, of which the following is a specification.

My invention relates to trimmers for filling cars, ships, and the like.

10 A great deal of material delivered by gravity into cars and vessels cannot, because of the rigid construction employed and the limiting area of the doors and hatchways, be distributed over the entire surface, but must 15 be shoveled or otherwise distributed by men employed for that purpose, this method being not only slow but very expensive.

Referring to the drawings, Figure 1 is a side elevation of my invention with parts 20 broken away; Fig. 2, a plan of non-rotatable bearing ring; Fig. 3, a cross-section of the same; Fig. 4, a plan of half the rotatable bearing ring; Fig. 5, an elevation of a half of the latter ring; Fig. 6, an enlarged elevation of 25 the lower portion of Fig. 7, looking toward the right; and Fig. 7, a side elevation of my invention in connection with a portion of a hatchway.

My invention is shown attached to the 30 chute of a car-dumper or coaling machine, extensively used along the Great Lakes for transferring coal from cars to vessels, but it is applicable to ore docks, coal docks, grain elevators, blast furnaces, stock bins, etc., 35 and to any purpose where gravity controlled distribution is desired.

On the drawings, 1 is a chute which may be of any desired form, its upper end leading to any source of supply of material to be fed 40 by gravity through said chute into a vessel or other receptacle. The lower end of the chute 1 is supplied with a ring 2, having preferably the circular ball-bearing surface 3, in which the groove 4 forms a race for the 45 anti-friction balls 5. It is to be understood that any other form of anti-friction devices, such as rollers, cones, or the like, may be employed, or that such devices may be entirely omitted, if desired.

50 Coöoperating with the ring 2 is rotatable ring 6, which is supported by the ring 2 and has the groove 7 registering with the groove 4 to form a completely closed race for the balls 5. The ring 6 has pendent therefrom, the 55 spout or chute 8 having the straight portion 9 and the inclined or deflecting portion 10.

In the chute is a deflecting plate or valve 11, mounted rigidly on the rock-shaft 12 so as to form a continuation of the straight side of the chute and then prevent any material from 60 passing along the deflecting portion of the chute, or to take an inclined position across the chute so as to form a temporary bottom therefor and deflect the material into the said deflecting portion of the chute. The shaft 65 12 is provided with a handle 13, having a catch 14 which locks in a notch at either end of the section 15. When the handle is thrown so that the catch is in one notch, the valve or plate 11 will close the deflecting portion of the chute, and when the handle is thrown in the opposite direction until its catch locks in the other notch, the said valve will deflect the material into the inclined portion of the chute. 75

It will be noted on Figs. 4 and 5, that the ring 16 is made up of distinct lateral sections which are secured together by the rivets 6', shown in Fig. 6 as extending through the triangular braces 6² shown on Figs. 5 and 6. 80 From Fig. 1 it will be apparent that the sections 6 can be assembled with the section 2 by moving the lateral sections into place with the grooves 4 and 7 registering.

On the top of the ring 6 is the circular rack 85 16, meshing with the pinion 17, carried on the shaft 18, which is driven by the pulley 19 thereon from any suitable source of power. The shaft 18 is carried in bearings on the chute 1. The upper end of the chute 1 carries the hoisting pulleys 20 by which the chute 1 with the pendent parts may be raised and lowered.

On Fig. 7, 21 shows the roof of a compartment in a vessel, 22 being a hatchway opening thereunto. If the straight spout 9 alone be used, the material would be deposited in the form of a frustum of a cone, as indicated by the lines 23, which lines would, even when the lower end of the spout is just at the opening 22, leave a large portion of the compartment unfilled between the material and the roof 21. In such a case, the filling of the compartment ceases and men must be employed to shovel the material away. The 105 charging and shoveling operations follow each other until the compartment is filled. With my invention, when the cone indicated by the lines 23 is formed, I swing the lever 13 from its upper to its lower position, thereby 110 moving the valve or plate 11 from the full line to the dotted line position shown on Fig.

1, whereupon the material is then deflected laterally through the chute or spout 10. At the same time pulley 19 is set in motion, whereby the material is distributed evenly 5 around the compartment and at a very much higher position than it was deposited by the chute or spout 9. By making the rotation rapid, centrifugal force would enter into the action of the spout 10 and the material could 10 be thrown to form almost a horizontal surface close under the roof 21, the whole apparatus being raised by the pulleys 20, as desired to raise the level of the distribution.

I claim—

15 1. In a device of the character described, a chute made in two sections, the lower section having a vertical and a lateral portion, a joint between the sections, on which joint the lower section is suspended and axially 20 rotatable, and coöperative means on the two sections for rotating the lower section.

25 2. In a device of the character described, a chute made in two sections, the lower section having a lateral portion, a joint between the sections, on which joint the lower section is suspended and axially rotatable, a circular rack on the lower section, a pinion carried by the upper section and meshing with the rack, and means for rotating the pinion.

30 3. In a device of the character described, a chute made in two sections, the lower section having a lateral portion, a joint between the sections, on which joint the lower section is suspended and axially rotatable, coöperative 35 means on the two sections for rotating the lower section, and means for raising and lowering the sections.

4. In a device of the character described, a chute made in two sections, the lower section 40 having a lateral portion, a joint between the sections, on which joint the lower section is suspended and axially rotatable, coöperative means on the two sections for rotating the

lower section, and means for raising and lowering the sections, the lower section being 45 free to permit movement of the sections both vertically and horizontally.

5. In a device of the character described, a chute composed of an upper section and a lower section, the lower section having a vertical and a lateral portion, a horizontal flange on the upper section, an inturned flange carried by the lower section and lying over the flange of the upper section, a circular rack carried by the lower section, a pinion carried by the upper section and meshing with the rack, means for rotating the pinion, and means for raising and lowering the chute. 55

6. In a device of the character described, a chute composed of an upper section having a horizontal flange with an upper bearing surface, a lower section having a horizontal in-turned flange with a lower bearing surface coöperating with the upper bearing surface, the lower flange being made in lateral sections, whereby the lateral sections may be assembled with the upper flange, a lateral extension on the lower section, and means for rotating the lower section. 60

7. In a device of the character described, a chute made in two sections, the lower section being rigid and having a vertical and a lateral portion, a joint between the sections, on which joint the lower section is suspended and axially rotatable, and coöperative means 75 on the two sections for rotating the lower section rapidly so that the material passing from the said lateral portion of the chute will be projected outwardly by centrifugal force. 80

Signed at Norwalk, Ohio, this 22nd day of August, A. D. 1907.

JOHN E. O'HEARNE.
